Primary Examiner—Caron Veynar*Assistant Examiner*—Ricky Pham(74) *Attorney, Agent, or Firm*—Seth Natter; Natter & Natter(57) **CLAIM**

The ornamental design for a foldable cooking sheet, as shown and described.

DESCRIPTION

FIG. 1 is a top plan view of a foldable cooking sheet showing my new design;

FIG. 2 is a bottom view thereof;

FIG. 3 is a front elevational view thereof;

FIG. 4 is an enlarged scale fragmentary front elevational view thereof;

FIG. 5 is a rear elevational view thereof;

FIG. 6 is a left side elevational view thereof, the opposite side being a mirror image;

FIG. 7 is a top plan view thereof with panels folded over one another;

FIG. 8 is a bottom view thereof with the panels in their FIG. 7 position;

FIG. 9 is a front elevational view thereof with the panels in their FIG. 7 position;

FIG. 10 is a rear elevational view thereof with the panels in their FIG. 7 position;

FIG. 11 is a right, side elevational view thereof with the panels in their FIG. 7 position; and,

FIG. 12 is a left side elevational view thereof with the panels in their FIG. 7 position.
